UNITED STATES PATENT OFFICE

2,396,446

NECKTIE

George W. Stein, Los Angeles, Calif.

Application June 9, 1944, Serial No. 539,448

1 Claim. (Cl. 2—153)

My invention relates to neckties of the particular type disclosed in the U. S. Letters Patent No. 2,153,650, issued to me April 11, 1939, and the principal objects of my invention are to generally improve upon and simplify the form of necktie shown in my aforesaid patent, as well as other existing forms of similar neckties and further, to provide a necktie with simple means for attaching same to the neck band for a collar or shirt and which attaching means is mounted on the bow portion of the tie, so that the latter may be shifted laterally in either direction so as to occupy a central portion between the front ends of the collar.

With the foregoing and other objects in view, my invention consists in certain novel features of construction and arrangement of parts which will be hereinafter more fully described and claimed and illustrated in the accompanying drawing in which:

Fig. 1 is a front elevational view of the front portion of a collar and showing a tie of improved construction attached thereto.

Fig. 2 is a rear elevational view of the tie with the rear wall of the knot portion broken away to show the internally arranged parts of the fastener.

Fig. 3 is a perspective view of the front portion of a collar with the front wall thereof broken away.

Fig. 4 is a plan view of the fastener.

Fig. 5 is a front elevational view of the fastener.

Fig. 6 is a vertical section taken on the line 6—6 of Fig. 5.

Fig. 7 is a front elevational view of a modified form of the fastener with parts broken away.

Referring by numerals to the accompanying drawing which illustrates a preferred embodiment of my invention, 10 designates the neck band of a collar and 11 the overlying outer wall of said collar and for the accommodation of the hooks of the tie fastener narrow pieces of tape 12 are secured by spaced rows of stitching 13 or otherwise to the outer face of the neck band thereby forming a series of half loops 14.

If desired short pieces of cord as shown in my aforesaid issued patent may be used in place of the tapes 12. The body of my improved tie comprises a knot portion K from which depends a flowing skirt portion S, and secured within the upper portion of the knot K, by stitching or otherwise, is a small plate like member 15 formed from a piece of thin metal, cardboard, plastics or the like, bent double so as to form two thicknesses of material, with the upper portion of ma-

terial spaced apart to form a transversely disposed loop 16.

Arranged to slide through loop 16 is a narrow elongated loop 17, preferably formed of resilient wire, and from the ends of said loop, extended portions of the wire project outwardly and upwardly to form curved arms 18 which terminate in depending hooks 19.

The knot portion K of the tie with its padding, 10 is formed around plate 15, so that same occupies a position in the upper central portion of said knot and thus the transverse loop 17 occupies a position within the upper portion of the knot, with the arms extending out through apertures A provided in the upper sides of said knot.

A staple like member 20 of wire or thread passes through the walls of loop 16 above and below the lower member of loop 17, thus serving as a stop to limit the sliding movement of said 20 loop and the arms 18 in both directions.

To apply the tie collar band, the front points of the overlying portion of the collar are turned upward and the hooks 19 are engaged in a pair of the flexible loops 14.

25 After the upturned points of the collar are lowered over the upper corners of the knot portion of the tie, the latter and plate 15 secured thereto may be shifted lengthwise of loop 17, so as to locate the knot in proper central position 30 between the forward ends of the overlying portion of the collar.

In Fig. 7 I have shown a modified construction wherein an arm 21 curved lengthwise and provided at its ends with depending hooks 22 is 35 stamped or cut from thin sheet metal, Celluloid or the like and provided with a centrally arranged longitudinally disposed slot 23.

This arm is mounted to slide through a loop 24a formed at the upper end of a plate 24 similar to 40 plate 15 and which is secured within the knot portion of the tie.

Obviously the fastening means comprising the parts 15, 17 and 18 may be associated with the knot portions of the bow ties as well as conventional four-in-hand ties.

45 Thus it will be seen that I have provided a necktie fastener which is simple in structure, inexpensive of manufacture and very effective in performing the functions for which it is intended.

50 The loop forming tapes 12 may be applied to both sides of the neck bands of reversible collars, also to the outer faces of the neck bands of shirts having attached collars.

It will be understood that minor changes in the 55 size, form and construction of the various parts

of my improved neckties may be made and substituted for those herein shown and described without departing from the spirit of the invention the scope of which is set forth in the appended claim.

I claim as my invention:

A necktie fastener comprising a plate adapted to be embedded in the knot portion of a necktie, the upper portion of said plate being formed into

a horizontally disposed loop, a horizontally disposed member provided with a centrally disposed elongated loop that is arranged for sliding movement through the loop at the upper end of said plate and a staple seated in the walls of the loop portion of said plate, one of the legs of which staple passes through the loop in said sliding member.

GEORGE W. STEIN.
